HAT BLOCKING MACHINE

John C. Hobgood, Lawrenceville, Va.

Application December 4, 1931. Serial No. 579,051

3 Claims. (Cl. 223—28)

The invention relates to machinery or devices designed for use in rejuvenating felt hats or the like and has for its general object the provision of a novel power driven machine by means of which a hat may be properly and efficiently steamed and ironed upon a suitable form so that the brim will be properly shaped.

An important object of the invention is to provide a machine of this character embodying an electric motor driven support carrying the hat to be worked upon together with a horizontally swingable and vertically swingable arm carrying a combined steaming and ironing or pressing member adapted to bear against the brim of the hat as the hat itself is rotated.

Another object is to provide a device of this character equipped with adjustable spring means for insuring proper firm engagement of the combined steaming and ironing member with the hat as the hat is rotated so that proper pressure may be applied to the desired location at all times.

Yet another object is to provide a machine of this character in which the ironing member may be electrically heated so as to effect drying out of the hat subsequent to the steaming operation.

An additional object is to provide an apparatus of this character which will be simple and inexpensive to make which will shift automatically in a lateral direction as the hat is rotated so as to remain constantly in engagement with the brim or crown thereof, which will be efficient and durable in service, positive in action and a general improvement in the art.

With the above and other objects and advantages in view, the invention preferably consists in the details of construction and the arrangement and combination of parts to be hereinafter more fully described and claimed, and illustrated in the accompanying drawings, in which

Figure 1 is a top plan view of the device the operative position of the arm and pressing member being shown by full lines and a horizontally swung away position being indicated by dotted lines.

Figure 2 is a side elevation of the machine with the normal or operative position of the pressing member and arm shown by full lines and the vertically disengaged position shown by dotted lines.

Figure 3 is an enlarged detail section through the steaming member this view being taken on the line 3—3 of Figure 2.

Figure 4 is a detail section taken on the line 4—4 of Figure 3.

Figure 5 is a vertical section taken on substantially the line 5—5 of Figure 2, and

Figure 6 is a horizontal cross section taken on the line 6—6 of Figure 5.

Referring more particularly to the drawings, the numeral 10 designates a suitable supporting stand, shelf or table upon which the entire mechanism to be described is mounted. Suitably secured upon this support or stand is the base 11 of an electric motor 12 which is arranged with its shaft 13 to extend vertically. This shaft carries a gear 14 or friction member engaging or meshing with a larger gear or friction member 15 so as to drive the latter, this friction member 15 being carried by a shaft 16 journaled through a bracket 17 extending laterally from the base 11. Suitably carried by the shaft 16 is a disk 16^a 70 provided with upstanding pins 16^b received within holes in a shell 18 have similarly or otherwise detachably mounted upon its top a form 19 adapted to receive the hat 20 to be worked upon, the form being open at its center so as to receive the crown of the hat, the brim of which rests upon the convexly curved top surface 21 of the form. It is of course intended that different shapes of forms be used depending upon the desired contour to be given to the hat brim 22, it being well known that some brims are much flatter or less curved than others and that some are, moreover, of quite different sizes. All of these variations are intended to be taken care of by having a series of plurality of the forms 19 85 any selected one of which may be placed upon the shell 18 depending upon the character, style or shape and size of the hat to be worked upon. Moreover, the shell and form may be replaced by a block adapted to engage upon pins 16^b rising 90 from the disk, so that the crown of the hat may be worked upon. Clearly, when the motor 12 is set into action the flange 18 carrying the form 19 and hat 20 will be rotated, the exact number of rotations per minute being immaterial but being possibly in the neighborhood of 40.

Mounted upon the support 10 in spaced relation to the base or bracket structure 11 is an upstanding stationary support 23 having an ear 24 thereon to which is pivoted, as at 25, an ear 26 on the lower end of a socket member 27 within which is rotatably engaged a cylindrical shank 28 adapted to have limited rotary movement and carrying a coupling or reducer 29 from the larger end of which extends a pipe 30 connected with a valve 31 to the opposite side of which is connected a second pipe 32 carrying the combined steaming and ironing device indicated as a whole by the numeral 33. The valve 31 is of the manually operative type and is represented as having a 110

control handle 34. The steaming and ironing member 33 is intended to be laterally movable with respect to the form 19 and hat 20 and it is for this reason that I have provided the shank 28 rotatable within the socket 27. For preventing accidental upward and downward displacement of the shank 28 while permitting limited rotary movement thereof, I may make use of a screw 35 passing through one side of the socket and engaging within a transverse slot 36 in the shank, it being quite clear that this will not interfere with the rotary movement of the shank while at the same time it will be prevented from being moved upwardly. A torsion spring 37 surrounds the shank 28 for normally urging the combined steamer and ironing device against the brim of the hat and this spring is disclosed as having one arm or end 38 engaged with the screw 35 and its other arm or end engaged about the coupling or reducer 29 as shown at 39. The pivot 25 permits the entire assembly comprised by the parts 26, 27, 28, 29, 30, 31, 32 and 33 to be moved bodily in a vertically swinging direction as will be quite apparent from an inspection of Figure 2 wherein this swung position is illustrated by dotted lines at the right hand side of the figure.

The combined steaming and ironing device indicated as a whole by the numeral 33 as above referred to is represented as comprising a shell 40 which may be formed as a casting and of suitable metal and which has a curved bottom wall 41 adapted to fit conformingly against the hat brim 22 and convexed surface 21 of the form 19 so as to give the desired and proper shape to the hat brim. This shell 40 is shown as divided by a partition 42 into two separate compartments 43 and 44, the former being for steam and having a pipe 32 communicating or connected therewith, the bottom of this compartment being provided with a plurality of perforations 45 so that steam entering the compartment may pass through and into or onto and also through the brim 22 of the hat. Within the compartment 44 is a suitable electric heater 46 to which are connected wires 47 leading through a protective tube 48 mounted in suitable clips 49. Moreover the steaming and ironing device 33 is preferably provided with a handle 50 by means of which it may be easily moved.

Steam for the steaming device or compartment 43 may be obtained from a supply pipe 51 extending through the support 10 and equipped with a valve 52 from which extends a flexible hose 53 connected with the smaller end of the coupling or reducer 29.

Assuming that the device has been constructed as shown and described, the operation is as follows: The hat 20 to be worked upon is placed in inverted position upon the form 19 so that its brim 22 will lie upon the convexed curved top surface 21 thereof. Of course the crown of the hat extends through the opening in the form and is located within the interior of the shell 18. The operator then grasps the handle 50 and moves the device comprised by the parts 26 to 53 into such position that the combined steaming and ironing device 33 will engage upon the upper surface of the brim 22 as clearly shown in Figures 1 and 2. The valves 52 and 34 must of course be opened so that steam will be supplied to the compartment 43 so that it may pass through the perforations 45 onto and through the brim of the hat. At the same time, the motor 12 is set into action so that the gears 14 and 15 will cooperate to drive the shaft 16, shell 18, form 19 and hat

20. In view of the fact that the hat is not circular but is always elliptical in shape it is apparent that as it rotates the device 33 moves alternately toward and away from the center of the hat but is always maintained in proper engagement therewith owing to the provision of the torsion spring 37. After the hat has made a few revolutions while steam issues from the perforations 45 it is apparent that the steaming action will be sufficiently carried out that it may then be discontinued. The valve 34 may then be closed so that no further steam will be supplied to the brim and the action of the electric heater 46 will then be such that the brim will be effectually dried or ironed into the proper final shape.

From the foregoing description and a study of the drawings, it will be apparent that I have thus provided a very simple and inexpensive device for the purpose specified and one which will be highly efficient for the purpose set forth. It is also clear that if such is desired the assembly comprised by the parts 26 to 50 may be swung vertically out of obstructing relation to the hat as shown by dotted lines in Figure 2. Moreover it is apparent that the assembly comprised by the parts 28 and 50 may move freely horizontally in accordance with the oscillatory motion of the hat and may also be pulled bodily away from the hat in a lateral direction as shown by the dotted lines in Figure 1. These possibilities together with the general operation should be readily apparent to one skilled in the art from the foregoing without any necessity for further explanation.

While I have shown and described the preferred embodiment of the invention, it should be understood that I reserve the right to make all such changes in the details of construction as well as in the arrangement and combination of parts as will not depart from the spirit of the invention or the scope of the subjoined claims.

Having thus described the invention, I claim.

1. In a machine of the character described, a power driven rotatable support carrying a centrally apertured form having a curved upper surface adapted to support a hat in inverted position with the hat brim upon the curved upper surface of the form, a stationary support, an upright socket pivoted upon said support for swinging movement about a horizontal axis, an arm structure having a depending trunnion mounted within said socket for rotation about a vertical axis, a combined steaming and pressing device carried by said arm and disposable in engagement with the hat brim, and torsion spring means connecting said socket member and the arm for urging said steaming and pressing device into constant engagement with the hat brim.

2. In a machine of the character described, a power driven rotatable support carrying a centrally apertured form having a curved upper surface adapted to support a hat in inverted position with the hat brim upon the curved upper surface of the form, a stationary support, a socket provided at its lower end with an ear pivoted upon said support for swinging movement about a horizontal axis, an arm structure extending normally substantially horizontally and having a depending trunnion mounted for limited rotary movement within said socket about a vertical axis, a combined steaming and pressing device carried by said arm and disposable in engagement with the hat brim, and a torsion spring surrounding the trunnion and having its ends connected with said socket member and the arm for urging said steaming and pressing device into constant

engagement with the hat brim during oscillatory movement of the hat resulting from its invariable elliptical shape.

3. In a machine of the character described, a motor driven shell carrying a form with a central aperture and a curved upper surface adapted to support a hat in inverted position, a stationary supporting member, a socket pivoted on said supporting member for vertical swinging movement, a shank mounted for limited horizontal movement within said socket and carrying a coupling, a steam conduit connected with said coupling, a

steam pipe connected with said coupling and carrying a combined pressing and ironing device, a control valve interposed in said pipe, said combined steaming and pressing device having separate compartments, one compartment being for steam, and the other containing an electric heater, and spring means cooperating with the shank and the coupling for maintaining the combined steaming and pressing device in engagement with the hat brim during rotation of the hat.
